UNITED STATES PATENT OFFICE.

GEORGE J. HOSKINS, OF SYDNEY, NEW SOUTH WALES, AUSTRALIA.

APPARATUS FOR MAKING CORES.

SPECIFICATION forming part of Letters Patent No. 699,175, dated May 6, 1902.

Application filed October 2, 1901. Serial No. 77,314. (No model.)

To all whom it may concern:

Be it known that I, GEORGE JOHN HOSKINS, a subject of the King of Great Britain and Ireland, and a resident of Ultimo, Sydney, 5 in the State of New South Wales and Commonwealth of Australia, have invented a certain new and useful Improved Apparatus for Making Cores for Cylindrical Castings, of which the following is a specification.

10 In giving effect to my invention the core-barrel is mounted on standards which are carried by a truck or traveler which runs on rails. Alongside the rail and parallel with the rail-track are standards which carry a feed-hopper so disposed that the hopper shall be caused to feed its contents tangentially upon the core-barrel on the side-nearest the standards which support the feed-hopper. Impinging against the core-barrel at the point 15 20 where the feed strikes it is a gauze-wire cylinder which is mounted upon an adjustable oblique axis. The axis is carried by a fork which is attached to a long spring, which will insure a pressure of the gauze-wire cylinder 25 30 against the core-barrel. Below the gauze-wire cylinder is a trough which will receive the superfluous material and liquid which is fed from the feed-hopper above. A lever is provided whereby the action of the 35 40 spring may be assisted and caused to press the wire cylinder more firmly against the core-barrel. Means are provided for rotating the core-barrel and, if necessary, imparting a forward movement to the truck carrying the core-barrel; but in order that the invention may be clearly understood reference is made to the accompanying drawings, in which—

Figure 1 is a front elevation of the apparatus. Fig. 2 is an end elevation of the same.

A A' are the standards.

B B is the truck, carried by wheels B' B' on rails b b.

The standards A A' support the core-barrel C, which is rotated by any suitable means, the means adopted and shown in the drawings being the axial motor D. Near the rails b b and parallel thereto are standards E E, which carry a feed-hopper F, which shall be 45 50 so situated as to feed its contents (which consist of a mixture of mucilage, sawdust, and water) tangentially upon the feed-hop-

per. Mounted near and parallel to the rails b b is a flat spring-support G, to the upper end of which is bolted a forked piece H, 55 which carries the axis of a gauze-wire cylinder J. In operation the axis will always be oblique, its obliquity being regulated and adjusted by hand, and when thus regulated it is secured in position by means of the nut 60 h. Should the spring G be insufficient to insure the necessary pressure of the wire cylinder J against the core-barrel C, such pressure may be transmitted to the cylinder J by pressing the lever H'. Below the gauze 65 cylinder is a trough K, which is intended to receive the superfluous mixture which falls from the hopper and the liquid which is expressed from the mixture by the pressure of the wire cylinder J. 70

It is believed that the rotation of the core-barrel C against the oblique wire cylinder J will cause the truck B to move in a forward direction; but means are provided whereby the forward movement of the truck shall be 75 automatically insured. The means shown in the drawings consists of a counter-shaft L, provided at one end with a bevel-wheel M, which gears with the bevel-wheel M' on the motor-shaft, and at the other end with the 80 pulley N, band O, and pulleys P on the axle Q of one of the truck-wheels B'. The means for rotating the core-barrel and imparting movement to the truck B may be greatly varied. The means shown in the drawings 85 merely exhibits one way that the desired object may be effected.

In Fig. 1 of the drawings the portion of the core-barrel to the right of the gauze-wire cylinder is shown covered with the sawdust composition, while the part to the left of the gauze-wire cylinder shows the plain surface of the core-barrel. 90

Having now described my invention, what I claim as new, and desire to secure by Letters 95 Patent, is—

1. In apparatus for making cores for cylindrical castings, in combination, a truck or traveler running on rails the said truck having means for carrying the cylindrical core-barrel, a fixed feed-hopper placed near the said means for carrying the core-barrel as described, a fixed revolving wire cylinder mounted to rotate in contact with the core-barrel, 100

means for insuring the pressure of the wire cylinder against the core-barrel, a trough below the wire cylinder and means for rotating the core-barrel, and for causing the forward travel of the truck all as herein specified.

5. 2. In a machine of the class described, a support for a core-barrel, means for moving said support in the direction of the axis of the core-barrel and for rotating said core-barrel, 10 a rotatable wire cylinder of less length than the core-barrel having its axis inclined to the

axis of the core-barrel, means for pressing the wire cylinder against the core-barrel, a feed-hopper above the point of contact of the core-barrel and cylinder and a trough below 15 the cylinder, substantially as described.

In witness whereof I have hereunto set my hand in presence of two witnesses.

GEORGE J. HOSKINS.
